STEAM FINISHING BOARD

Frank H. Richterkessing, Louisville, and William M. Cissell, St. Matthews, Ky., assignors to W. M. Cissell Mfg. Company, Incorporated, Louisville, Ky., a corporation of Kentucky

Application February 26, 1948, Serial No. 11,221

6 Claims. (Cl. 68—6)

1

This invention relates to a steam finishing board for pressing garments and other articles.

It is desirable in such a finishing board to provide means for passing the steam through the garments or articles being pressed thereon and also to provide means for drawing air into the interior of the board through said garments in order to dry them; also to maintain the board heated at all times during its operation independently of the aforesaid means.

It is a primary objective of the invention to provide a steam finishing board embodying the aforesaid features in a novel simplified manner.

In particular it is an object of the invention to provide such a finishing board of cast metal construction having heating tubes embedded therein in a manner to provide a highly efficient heat conducting relation between the tubes and the board.

A further object is to provide such a board including a perforated cover plate supported in a manner to have a maximum amount of heat conducted thereto from the board.

A still further object is to provide a novel arrangement wherein the said cover plate cooperates with the board to define a closed chamber having steam injecting means associated therewith for the purpose of steaming garments supported on the board.

A still further object is to provide a novel steam actuated suction means associated with the aforesaid chamber to draw air through the garments.

A still further object is to provide a suction control valve for use alternatively in conjunction with conventional suction means in place of the aforementioned steam actuated suction means.

A still further object is to provide a simplified and easily assembled manifold unit facilitating the connections of the various steam tubes to the board.

An additional object is to provide such a board with control pedals for the various steam valves arranged so that the several control pedals and their associated mechanisms may embody a number of similar standard parts in their respective constructions.

In this application we show and describe only the preferred embodiment of the invention simply by way of illustration of the practice thereof, as by law required. However we recognize that the

2

invention is capable of other embodiments and that the several details thereof may be modified in various ways all without departing from the invention. Accordingly the drawings and descriptions herein are to be considered as merely illustrative and not as exclusive.

In the accompanying drawings:

Figure 1 represents a perspective view of the preferred embodiment of the invention;

10 Figure 2 an end elevation thereof;

Figure 3, a plan view, on an enlarged scale relative to Figure 1, of the finishing board casting or body with the fabric cover and the perforated cover plate removed;

15 Figure 4, a section on the line 4—4 of Figure 3 looking in the direction of the arrows;

Figure 5, a greatly enlarged fragmentary transverse section on the line 5—5 of Figure 4 looking in the direction of the arrows;

20 Figure 5A, a view corresponding to Figure 5 showing a modified arrangement for creating a vacuum in the finishing board;

Figure 6, a section on the line 6—6 of Figure 4 looking in the direction of the arrows;

25 Figure 7, a detail section on the line 7—7 of Figure 3 looking in direction of the arrows;

Figure 8, a view partly in section on line 8—8 of Figure 1 looking in the direction of the arrows and showing the pedestal or base portion of the finishing board in plan;

30 Figure 9, a section view on the line 9—9 of Figure 1 looking in the direction of the arrows and showing the bottom of the finishing board in plan;

Figure 10, a detail end elevation of the stand or support for a pleat setter which may be used in conjunction with the invention; and,

Figure 11, a detail plan view of the stand shown in Figure 10.

40 Referring now in detail to the accompanying drawings, the reference character 1 designates a pedestal or base which may be of suitable, preferably cast iron, construction and hollow in order to house the operating mechanisms associated

45 with the various control pedals 2, 3 and 4 respectively mounted thereon. Projecting upwardly from this pedestal 1 is a standard or column 5 on which is supported the steam finishing board, designated 6 in its entirety.

In accordance with usual practice a tray T of

conventional construction may be supported beneath the finishing board 6 to catch any depending portions of garments being processed on the board 6 and prevent same from contacting the floor. Such a tray T may be supported by means of an angle bracket B fixed to the supporting column 5.

The finishing or pressing board comprises an elongated casting 7 of a suitable metal, such as aluminum, which is suitably secured to the upper end of the column 5 and supported at a convenient height in a substantially horizontal plane.

By reference to Figures 3, 4 and 7, it will be noted that the casting 7 is formed with a basin or indentation in its upper surface, said basin comprising a relatively deep central trough 8 extending along the longitudinal axis of the casting, and a relatively shallow marginal portion 9 surrounding the trough 8. A marginal wall or rim 10 bounds said basin.

A plurality of relatively spaced bosses 11 integral with the casting 7 project upwardly to a common level from the bottom of the marginal portion 9 of the basin, and a perforated steaming plate or cover plate 12, which may be of stainless steel or other preferably smooth metal construction conforming in shape to the configuration of said basin, is supported on these bosses 11 in intimate surface engagement with each.

The perforations 13 on the plate 12 are preferably uniformly distributed, as shown in Figure 7, and the plate is snugly seated within the marginal wall or rim 10 of the basin to form a closed chamber which may be in communication with suitable steam and/or suction lines to expel steam or draw air through the perforations in the plate 12.

In accordance with usual practice, the plate 12 and adjacent surface portion of the casting 7 are provided with a suitable porous fabric covering comprising a pad 14 and a cover 15 to provide a suitable working surface on which the garments or other articles may be supported.

In order to maintain the working surface of the board heated at all times during its operation, independently of the steam supplied to the basin or chamber therein, a suitable number of heating tubes 16 may be embedded in the lower face or bottom of the casting 7, preferably beneath the marginal portion 9 of the basin so that the heat from said tubes will be effectively transmitted by conduction through the casting and the bosses 11 to the plate 12, it being noted that each of the bosses 11 in the preferred embodiment has a flat surface area or top in intimate engagement with the plate. The relatively equal distribution of these bosses 11 will contribute to an even distribution of the heat to all portions of the plate 12.

We have found that one highly efficient manner of assembling the heating tubes 16 in the casting 7 is as illustrated in Figures 7 and 9 of the drawings. In this arrangement, the bottom or lower face of the casting is formed with a plurality of preferably equidistantly spaced grooves or recesses 17, each of generally U shape, extending on opposite sides and around one end of the trough 8 beneath the marginal portion 9 of the basin or chamber and in concentric relation with each other.

The U-shaped steam tubes 16, which may be of copper or other suitable conductive metal, are disposed in these respective grooves 17, and retained in place by means of metal inserts 18 which may be formed by pouring a suitable mol-

ten metal, such as lead, into the grooves 17 around said tubes. The inserts 18 are in intimate surface engagement with both the tubes 16 and the walls of the grooves 17 and thus provide efficient heat conducting paths between the tubes 16 and casting 7.

If desired auxiliary retaining means consisting of metal bars 19 extending across the several grooves and secured to the lower surface of the casting 7 at suitable locations, may be employed to further secure the several inserts 18 and tubes 16 in their respective grooves.

The chamber or basin 8, 9 has a steam injection port 20 and a suction port 21 (Figure 4) communicating therewith, preferably through a common passage 22 which is formed by projecting one end of the trough 8 longitudinally beyond the remainder of the basin and sealing the projecting end and top of same respectively, as by 15 the flange portion 23 and an overlying shelf 24, both preferably formed as integral parts of the casting. The bottom of trough 8 slopes downwardly to the passage 22 as shown in Figure 4.

In the preferred embodiment of the invention, 20 the steam injection port 20 is formed in a nozzle 25 which projects upwardly through an opening in the bottom of the trough extension or passage 22, as in Figure 6.

Preferably this nozzle 25 is formed as part of 25 an integral manifold casting 26 which extends transversely beneath the shelf 24, and provides a simple efficient junction or connection between the finishing board casting 7 and the various steam lines associated therewith.

Such a manifold casting or junction member 26 consists of a medial bridge section 27 disposed beneath the passage 22 and carrying the nozzle 25 which projects upwardly through said passage into the interior thereof, said nozzle having its 30 port 20 in communication with a steam supply line 28 threaded into the bottom of said bridge section; and hollow steam compartments 29 and 30 respectively disposed on opposite sides of the passage or trough extension 22. The opposite ends of the respective steam tubes 16 are received in these compartments, and a steam supply line 31 is in communication with one of said compartments 30, while a steam return line 32 is disposed in communication with the other of said compartments 29. Thus it will be seen that steam will be caused to circulate through the tubes 16 from the supply or intake compartment 30 to the exhaust compartment 29.

By virtue of the foregoing arrangement of the 35 manifold casting 26 and steam pipes 16 on the finishing board, it will be readily apparent that said pipes and manifold may be completely operatively assembled with each as a unit, and this preassembled unit then operatively positioned on the finishing board and secured thereto by pouring molten metal in the grooves, as at 18, or otherwise. Thus the assembly of the complete finishing board is greatly simplified and expedited, with resulting economy of production.

Referring now to Figures 1 and 2, it will be seen that a steam chest 33 is mounted on the supporting column 5, preferably being supported on a bracket 34 integral with said column, and steam is supplied to this chest from any suitable source by means of the supply line 35, which may be equipped with a usual hand valve 36 to shut off the flow of steam when desired.

The steam supply line 31 is connected to the steam chest to convey steam therefrom to the heating tubes 16, and the exhaust or return line

32 for the heating tubes is connected through the bottom of the steam chest 33 to the main exhaust or return line 37. The return line 37 may be provided with a conventional condensation trap 38 and a hand valve 39, in accordance with usual practice.

The steam supply line 28 to the injection nozzle 25 is connected to the steam chest 33 through a control valve 40 (Figure 1) which may be of any conventional construction and which is normally biased to closed position, as by means of a spring 41 exerting resilient closing pressure against the valve control lever 42.

The valve control lever 42 is of bell-crank form, pivoted at 42a, and has an arm 42b connected to one of the foot pedals 2, which may be depressed to open the valve and produce a flow of steam into the interior of the finishing board through the nozzle 25.

To provide such a connection, we prefer to utilize a construction such as shown in Figure 8, in which the pedal 2 is carried at one end of a relatively integral crank 43, which in turn is fixedly secured to one end of a rock shaft 44 journaled for rotary movement in the interior of the hollow base 1. The other end of this rock shaft 44 projects from the base 1 substantially beneath the steam chest 33. A crank 45 is fixed to this projecting end of the rock shaft 44, and, as shown in Figure 2, this crank 45 and the valve control lever 42 are operatively connected by a connecting rod 46 which is pivotally secured to the free ends of both of said members 42b and 45, as shown.

The suction or exhaust port 21 of the finishing board may be defined by one end of the bore or passage extending through a hollow elbow fitting 47 having one end projecting through the bottom of the trough extension of passage 22. The other end of this fitting 47 has a Venturi tube 48 coupled thereto, and a steam injection nozzle 49 mounted in the fitting has its discharge end directed into the Venturi tube in operative relation thereto to draw air through the outlet port 21 when steam is passed through said nozzle 49, all in accordance with well known principles. The Venturi tube discharges into a usual discharge pipe 50 of which a portion only is shown.

The injection nozzle 49 is placed in communication with the steam chest through a bore 51 in this fitting, a supply pipe 52 threaded into said bore, and a control valve 53 interposed between the supply pipe 52 and the steam chest 33 to control the flow of steam to the nozzle 49.

This valve 53 may be similar to the aforementioned valve 40, and connected to a foot pedal 3 for control thereby, by mechanism similar to that heretofore described in conjunction with valve 40, and including a rock shaft 44a, a crank 45a mounted thereon, and a connecting rod 46a extending between and pivotally connected to the respective free ends of the said crank 45a and the valve control lever.

Where it is desired to connect the exhaust port to a vacuum tank or source of suction other than that shown in Figure 5, the fitting 47 may be replaced by an elbow fitting 47', such as shown in Figure 5A, which is connected to the source of suction or suction device by a pipe 70. A vertical bore 71 passes through the wall of the fitting and a valve stem 72 is slidably disposed through this bore. A valve member 73 carried by the stem 72 is disposed to seat over the upper end of the opening through this fitting, and a relatively coaxial valve spring 74 is associated

with the valve stem to normally maintain the valve member 73 in seated position, as shown.

A depending bracket 75 mounted on the fitting 47' has a lever 76 medially pivotally connected thereto, as at 77, one end of the lever being in contact with the lower end of the valve stem 72 for swinging movement in the axial plane thereof, and the other end of the lever being pivotally connected to the connecting rod 46a aforementioned.

With this arrangement it may be seen that the pedal 3 may be depressed to swing the lever 76 and raise the valve member 73 from its seat. It follows that this will permit the air and/or steam to flow from the interior of the finishing board through the fitting 47' and pipe 70 to a suction device or vacuum chamber of any conventional type.

In order to facilitate the employment of a steam or steam electric iron in conjunction with the finishing board, there is provided a hollow standard 54, which projects upwardly from the shelf 24 and supports an auxiliary steam chest 55 at its upper end.

This auxiliary steam chest is connected to the steam chest 33 by means of a supply line 58 extending from said chest 33 upwardly through the hollow standard 54, all as generally indicated in Figure 2. A horizontal arm 57 fixed to the steam chest 55 supports the steam supply line 58 for the iron (not shown).

This supply line 58 communicates with the steam chest 55 through the control valve 59 mounted on said chest. This valve 59 is preferably constructed and operates in a manner similar to valves 40 and 53 aforementioned, being normally maintained in closed position by the spring 60.

In order to permit control of the valve 59 by a foot pedal 4 and associated mechanism similar to that aforementioned in connection with the pedals 2 and 3, the operating lever 61 of the valve is connected by a tension element or chain 62 to a crank arm 63 of a rock shaft 64, which is rotatably mounted on the under side of the shelf 24; all as shown in Figures 2 and 5. A further crank arm 65 carried by the shaft 64 (and shown in Figure 9) is operatively connected to the foot pedal 4 by a connecting rod 46b and associated mechanism including a crank 45b and rock shaft 44b, all constructed and arranged in a manner similar to that hereinbefore described in conjunction with other foot pedals 2 and 3.

Thus it will be apparent that the foot pedal 4 may be actuated by downward pressure to open the valve 59 and permit passage of steam through the iron supply line 58.

In connection with the foot pedals 2, 3 and 4, it will be noted that said pedals are of identical construction, as are the cranks 45, 45a and 45b while the rock shafts 44, 44a and 44b are all formed of standard stock, differing only as to their length.

Such standardization of parts is made possible by virtue of the fact that the several shafts extend parallel to each other and diagonally to the longitudinal axis of the base 1, so that the pedals may be attached to corresponding ends thereof at points in relative alignment with the longitudinal axis of the base 1, despite the uniform lengths of the crank arm embodied in the pedal castings.

Additional attachments for facilitating the use of the invention may comprise a conventional rest or support R for the iron. Such a rest may

consist of a rectangular piece of asbestos or other insulating material.

Also it is desirable to provide a support **S** for a usual pleat setter, whereby same may be positioned conveniently adjacent to the finishing board. Such a support **S** is illustrated in detail in Figures 10 and 11 and comprises a supporting bracket **80**, fixed to the shelf **24**. A rod **81** carried by the bracket **80** extends substantially parallel to the finishing board and to one side thereof, and the stand **S** is supported on this rod with one edge parallel to and closely adjacent the finishing board.

In the operation of the finishing board, which is believed to be apparent from the foregoing, the garment or fabric to be treated is placed on the surface of the board **6**.

Where it is desired to steam said garment or fabric, the pedal **2** may be depressed to cause a flow of steam through the nozzle **25** and beneath the perforated plate **12**, thence upwardly through the perforations **13** in said plate and the layers of porous material **14** and **15** to the garment or fabric.

Where it is desired to reverse this process and dry the garment by drawing air downwardly into the board through same, this may be effected by foot pressure on the pedal **3**, with consequent actuation of the vacuum or suction means shown in Figures 5 and 5A.

Depression of the remaining pedal **4** opens the valve **59** to permit the passage of steam to the supply line **58** for the iron.

During the operation of the board, the surface thereof will remain heated at all times by the action of the heating tubes **16**, and the constant flow of steam through.

We claim:

1. A steam finishing board comprising an elongated metal body formed with a basin in its upper surface, said basin comprising a relatively deep central trough and a relatively shallow marginal depression surrounding said trough, said body being formed with a fluid passage in longitudinal alignment and communicating with one end of said trough, the bottom of said trough sloping downward to said passage, a plurality of relatively spaced bosses integral with the bottom of said marginal depression, a perforated plate supported on said bosses and covering said basin, and heating tubes in the lower surface of said body beneath said marginal depression to supply heat to said perforated plate by conduction through said body and said bosses, said body being formed with recesses in its lower face for receiving said respective tubes, and metal inserts in said recesses around said tubes to provide an efficient heat conducting path between said tubes and said casting, in combination with a junction member disposed across said passage beneath said body, said member comprising a medial bridge portion disposed beneath said passage, a steam injection nozzle carried by said bridge portion in communication with said passage, and being formed with compartments on opposite sides of said passage respectively communicating with the opposite ends of said tubes, steam supply and exhaust lines respectively communicating with said compartments to circulate steam through said tubes, a steam supply means communicating with said nozzle, a control valve for said supply means, a suction fitting communicating with said passage, and pedal controllable means for exerting suction therein.

2. A steam finishing board comprising a metal

body formed with a basin in its upper surface, said basin comprising a relatively deep central trough and a relatively shallow marginal depression adjoining said trough, said trough gradually increasing in depth towards one end thereof, in combination with means for injecting steam into said trough, and suction means communicating with said trough at said end whereby drainage of condensate from said basin through said suction means will be facilitated, said suction means comprising a hollow fitting having one end in communication with said trough, a Venturi tube coupled to the other end of said fitting, and a steam injection nozzle mounted in said fitting in operative relation to said Venturi tube to cause suction in said trough responsive to the passage of steam through said nozzle.

3. A steam finishing board comprising an elongated metal body having a series of substantially parallel U-shaped grooves in its bottom face, a similar series of U-shaped steam pipes disposed in said respective grooves, conductive metal in said grooves around said pipes to secure the latter in intimate heat conductive relation with said board, the top surface of said board being formed with a trough therein midway between the legs of said respective U-pipes and projecting beyond the relatively spaced opposite ends thereof, a manifold on the bottom of said board extending across said trough and having separate intake and exhaust compartments on opposite sides of said trough communicating with the respective opposite ends of said pipes, a steam injection nozzle carried by said manifold between said compartments and projecting into said trough, steam intake and exhaust lines respectively communicating with said intake and exhaust compartments to circulate steam through said pipes, and a steam supply line communicating with said nozzle.

4. A steam finishing board comprising an elongated metal body, a series of U-shaped steam pipes disposed beneath and in heat conductive relation with the bottom of said board, the top surface of said board being formed with a trough therein midway between the legs of said U-shaped pipes and projecting beyond the relatively spaced opposite ends thereof, a manifold on the bottom of said board extending across said trough and having separate intake and exhaust compartments on opposite sides of said trough receiving and communicating with the opposite ends of said pipes, and a steam injection nozzle carried by said manifold between said compartments and projecting into said trough.

5. A steam finishing board comprising an elongated metal board member, a series of U-shaped steam pipes disposed beneath and in heat conductive relation with said member, the top surface of said member being formed with a trough therein midway between the legs of said U-shaped pipes and projecting beyond the relatively spaced opposite ends thereof, a manifold having separate closed compartments secured to and respectively communicating with the opposite ends of said U-shaped pipes, and steam injection means carried by said manifold in communication with said trough.

6. A steam finishing board comprising an elongated metal body having a series of substantially parallel U-shaped grooves in its bottom face, a similar series of U-shaped steam pipes disposed in said respective grooves, metal arranged in said grooves around said pipes to secure the latter in place and provide heat conductive paths be-

tween said pipes and said body, the top surface of said board being formed with a trough therein midway between the legs of said respective U-shaped pipes, a manifold member having separate closed compartments secured to and respectively communicating with the corresponding opposite ends of said pipes, and steam injection means carried by said manifold member in communication with said trough.

FRANK H. RICHTERKESSING.
